MEDICAMENT DISPENSER

David W. Osborne, 163 Columbia Ave., Elmhurst, Ill.

Filed July 29, 1963, Ser. No. 76,025

Term of patent 14 years

(Cl. D83—1)

figure 1

The undisclosed side of the article disclosed in FIGURE 3 is substantially the same as the side shown. The bottom is substantially flat and unornamented.

I claim:

The ornamental design for a medicament dispenser, as shown and described.
